UNITED STATES PATENT OFFICE

2,456,532

ROD BENDER

Peter L. Perazzo, Napa, Calif.

Application December 1, 1945, Serial No. 632,237

5 Claims. (Cl. 153—15)

1

The invention relates to a device for shaping rods or bars to provide various bends therein.

An object of the invention is to provide a particularly effective hand-operated rod bender for its purposes.

Another object is to provide a rod bender in which all bending operations to provide variously bent rods or bars may be effected by use of the same bending unit.

The invention possesses other objects and features of advantage, some of which, with the foregoing, will be set forth or be apparent in the following description of a typical embodiment thereof, and in the accompanying drawings, in which:

Figure 1 is a perspective view of a rod bender embodying my invention and conditioned for receiving a straight rod or bar for the bending thereof.

Figure 2 is a plan view of the bender, a straight rod to be bent being fragmentarily shown as positioned on the bender for an initial bending thereof.

Figures 3 and 4 are enlarged sectional views of the bender at the lines 3—3 and 4—4 in Figure 2 respectively.

Figure 5 is an enlarged perspective view of a bearing sleeve of the bender.

Figure 6 is a fragmentary section of a bearing sleeve axially removed from its normal position about a former pin of the bender.

Figures 7 to 14 inclusive are plan views showing the successive steps of bending an initially straight rod to provide an eye intermediately therein, as exemplifying typical operations with the bender.

As particularly illustrated, a bender 11 embodying the features of present invention comprises an anvil or base member 12, and a lever arm member 13 which is pivoted to the base 12 at a pivot bolt 14. The base 12 is of generally rectangular form in plan and is provided at its bottom with ears 15 extending longitudinally from it and provided with bolt holes 15' for use in bolting it to a work bench or other support. The top of the base 12 is stepped at an intermediate cross-line thereof to provide flat upper and lower mutually parallel faces 16 and 18 respectively. The head portion 17 of the arm member 13 supportedly rests upon the lower base face 18 and has its top face 19 flush with the upper face 16 of the base.

The upright step face provided between the mutually adjacent edges of the upper and lower base faces 16 and 18 has mutually offset plane portions 21 and 22 which are connected by a cylindrically curved face portion 23, said face portions being perpendicular to the faces 16 and 18, while the portions 21 and 22 extend in mutually parallel relation from opposite sides of the base perpendicular thereto. The stepped base 12 is

5 10 15 20 25 30 35 40 45 50 55 60

2

appropriately cored out from beneath to lessen its weight, and the curved portion 23 of the step face comprises an extension of one side of a generally elliptical opening 24 extending between the lower base face 18 and a core space 25 in the base bottom. The opening 24 is arranged to provide for the gravity removal and escape of scale or other extraneous matter from the base face 18 as the head 17 is more or less swung across it from over the face 18 to sweep the matter into it.

The pivot bolt 14 has its head fully countersunk in the top of the member 13, extends through the lower base portion providing the face 18, and is secured by a primary nut 27 and a locknut 27', the pivot bolt being approximately stepped to a larger size at and above the plane of the face 18 to prevent an undue tightening of the hinge joint provided by it. At the end thereof opposite its pivotal axis, the arm head member 17 is provided with a socket 28 of uniform polygonal cross-section for removably and complementarily receiving one end of an extension bar 29 of suitable length for providing the leverage required for the bending of a rod or bar with the present lever arm. Mutually opposed annular grooves 30 in the under face of the arm head 17 and in the base face co-axially and jointly receive a sealing ring 30' of felt or the like for preventing the passage of grit from the face into the pin bearings.

It will now be noted that the head 17 of the lever arm member 13 has a cylindrically convex end face portion 31 which is concentric with the pivot bolt axis, and is tangent to flat face portions 32 and 33 extending to mutually parallel side face portions 34 and 35 of the head and making equal angles therewith, whereby the head portion adjacent the pivot bolt 14 is symmetrical to a plane through the pivot axis and parallel to the side head faces 34 and 35. The portion of the head 17 which provides the socket 28 for receiving the actuating bar 29 is somewhat narrower than is the head between its faces 34 and 35, is bounded on one side by a continuation of the face 35, and has its other side face 36 parallel to the face 35 and connected with the face 33 of the head by an obliquely extending face 37.

In the present structure, the step face portions 21 and 22 and 23 are so related to the head form and the axis of pivoting of the member 13 that the head edge faces 34 and 33 may respectively be disposed flat against the step faces 21 and 22 as stops which determine the operative range of the member 13. The arrangement is such that the swinging range of the member 13 between its limiting positions against the base faces 21 and 22 is about one hundred sixty degrees. Also, as is hereinafter brought out, the possible swinging of the member 13 from the position shown for it in Figure 7 toward its limiting position against

the face 21 so exceeds ninety degrees that a right angle bend may be provided in an engaged rod.

Former pins extend upwardly from the mutually coplanar faces 16 and 17 of the base and head for variably engaging a rod or bar R which has been suitably disposed with respect to the pins while resting on said faces. In the present structure, pins 41 and 42 and 43 are mounted in the head 17 to extend perpendicularly from its upper face 19, the plane of the pins 41 and 42 being perpendicular to the plane of the head face 35, and the plane of the pins 42 and 43 being parallel to that of the face 35 whereby the pins are in a rectangular L-shaped arrangement. Also, the pins 41 and 43 are at like distances from the pin 42, and the pins 41 and 42 are equally spaced from the aforesaid longitudinal plane of the head through the pivot bolt axis, whereby they are also equally spaced from the latter axis. It is to be further noted that the plane of the pins 41 and 42 lies at the handle side of the axis of swinging of the lever arm at a distance from said axis which approximates the clearance between the opposed pin faces, while the pin 43 lies at the handle side of said plane.

The base 12 provides upstanding former pins 44 and 45 and 46 and 47. Pins 44 and 45 and 46 are disposed in a common plane which is perpendicular to the side faces of the base, and the pins 44 and 45 are substantially tangent to the step face portion 21. The pins 46 and 47 define a plane which is parallel to the side faces of the base, and is therefore perpendicular to the plane of the pins 44 and 45 and 46, it being particularly noted that the plane of the pins 46 and 47 is arranged to be coplanar with that of the head pins 42 and 43 when the head is disposed in the position shown for it in Figure 2. The mutual spacing of the pins 45 and 46 and 47 of this L-shaped arrangement of pins on the base is the same as that for the pins 41 and 42 and 43 of the lever arm, and the pin-spacing distance slightly exceeds the width of the largest rod to be laterally bent with the present bender.

The various pins 41 to 47 inclusive are of like diameter, and have reduced bases which are fixed in complementary sockets extending into the base and head from their top faces; each pin base may have a driving fit in its socket. The extending portions of the pins 46 and 47 rotatably mount bearing sleeves 48 having the same exterior diameters as the other pins, and being retained on their pins by means of heads 46' and 47' of the different pins; the pins 46 and 47 are provided with exterior bearing sleeves because a rod being bent must move longitudinally while engaging these pins, as will hereinafter be apparent. It will be understood that all of the pins are eccentric to the pivotal axis of the lever arm.

Having the bender base 12 and arm 13 related as in Figure 2 wherein the former pins 46 and 47 and 42 and 43 are in generally coplanar relation, a straight rod R to be bent is disposed between the aforesaid array of pins and the pins 45 and 41, with the rod point at which a bend is to be provided disposed opposite the pin 41; the present rod R is shown as of circular cross-section, but may comprise a bar of polygonal cross-section. With a rod R so disposed, a rocking of the arm 13 to swing it to move its face 35 forwardly toward the step face 21 of the base is arranged to effect the bending of the rod around the pin 41 as a template, with the interior bend radius determined by the size of the pin 41, it being under-

stood that a right-angle or acute-angle bend in a rod or bar cannot have its inside too sharp because the material at the outside of the bend would then be so weakened as to provide a bend lacking in requisite strength.

By way of illustrating possible bending operations with the present bender, Figures 7 to 14 disclose a specific succession of bending steps by which a rod R may be bent to provide an eye R' at an intermediate point thereof. The eye bend R' may be the only bend produced in the rod, or may be one of several like or different types of bends.

Referring specifically to the bending of a rod R to finally provide the eye R', Figure 7 is seen to disclose a relation of the arm 13 to the base 12 in which the rod is first positively engaged for bending it around the pin 41, the arm 13 having been pulled slightly forwardly, and the rod then being engaged only by the pin 46 of the base and by the pins 41 and 43 of the arm; if the rod portion extending from the point of bending toward the pins 46 and 47 is too short to reach the base pin 46, it may engage the base pin 41. Having the rod R engaged by the three former pins 46 and 41 and 43 as described, the handle 13 is pulled forwardly to provide a desired degree of bending which, with the present arrangement of bending pins, may be anything from a small angle to an angle which is somewhat greater than a right-angle when the rod is released from the bender. Recalling that rods of most materials are more or less resilient, it will be understood that such a rod must be over-bent while engaged by the bender.

Figure 8 discloses the relation of the bender elements to the rod R which has been bent to provide a right-angle bend; because of the swinging of the pin 41 toward the pin 47 as the bend is formed, the rod portion opposite the pin 47 is finally brought against the latter pin rather than the pin 46. In reference to the arcuate swinging of the pin 41 and the other pins 42 and 43 with the lever arm 13, it will be understood that these pins comprise movable, rather than fixed, former pins or templates as the lever arm is actuated for a bending operation upon a rod engaging any of them. It is to be noted that while an angular bend is being formed with the rod engaging a pin 46 or 47, an appreciable longitudinal movement of the pin-engaging rod portion is effected, this making the provision of the bearing sleeves 48 on these pins particularly desirable.

Having provided a substantially right-angled bend in the rod, the rod is remounted on the bender in the position shown in Figure 9, wherein the pin 41 is disposed at the inside corner of the bend and the base pin 44 and arm pin 43 are disposed at the outside of the different arms of the bend. A swinging forward of the arm 13 further bends the rod toward the formation of a sharp V-bend approaching a U-bend when the arm reaches a limiting position determined by the engagement of the arm head 17 with the step face portion 21 of the base. As the arm is swung toward and beyond the position shown for it in Figure 10 the outer side of the bend may engage the base pin 47 and the arm pin 42 as aiding the sharpening of the bend about the pin 41.

With the present arrangement of bending pins, the operation which is illustrated by Figures 9 and 10 has not produced a true U-bend, and the latter may be effected by mounting the bent rod in the manner shown in Figure 11 wherein the bend is looped around the base pin 47 and has

its different legs engaging the arm pin 41 and the base pin 45. With the bent rod so mounted, a forward swinging of the arm may provide a true U-bend in which the sides are mutually parallel, as is indicated in dash lines in Figure 11. A continued forward swinging of the arm 13 to the position shown in Figure 12 will produce the half-eye bend shown in Figure 13. It will be noted that the present bending use of the arm 13 finally results in the cooperation of the base pin 45 and the arm pin 41 at substantially the same distance from the pin 47. Having formed the half-eye bend of Figure 13, an operator may turn the bend over the base pin 47 with its legs between and engaged with the pins 44 and 41, and rock the lever arm forwardly to complete the eye R' which was to be provided.

From a consideration of the foregoing illustrated manner of providing an eye in a rod or bar, it will be understood that the pins 41 to 47 inclusive are arranged to be variously utilized in bend-forming operations, and that the present bender may be otherwise applied to a rod or bar for providing one or more bends therein. Since the various pins operate in a common plane upon a rod or bar resting upon the base and arm faces 16 and 19 respectively, it will be understood that a twisting of a rod being bent out of its plane of bending is practically impossible, whereby an operator may use the present bender with particular confidence in the bending of rods to a specified degree or to a pattern.

From the foregoing description taken in connection with the accompanying drawings, the advantages of the construction and use of the present device will be readily understood by those skilled in the art to which this invention appertains. While I have described the features and principles of use of a rod bender which I now consider to comprise a preferred embodiment of my invention, I desire to have it understood that the showing is primarily illustrative, and that such changes and developments may be made, when desired, as fall within the scope of the following claims.

I claim:

1. In a rod bender, a base providing a flat upper face, former pins extending upwardly from said base face, a lever arm mounted on said base for swinging about a fixed axis perpendicular to the upper base face and having a flat upper face coplanar with said base face, and former pins extending from the upper face of said lever arm in eccentric relation to its axis of swinging, said former pins of the base and lever arm being so related as to engage a rod disposed upon said upper faces of the base and arm as the sole means for bending the rod about one of them as the lever arm is swung from the position it had when the rod was placed upon the base and lever arm.

2. In a rod bender, a base providing a flat upper face, an L-shaped line of mutually spaced former pins extending fixedly from said base, a lever arm having a head end portion pivoted on said base for a swinging of the arm about a fixed axis perpendicular to the upper base face and having a flat upper face coplanar with said base face, an L-shaped line of mutually spaced former pins extending fixedly from said upper face of the lever arm head in eccentric relation to its

axis of swinging, said former pins of the base and lever arm being so related as to cooperatively engage a rod disposed upon said upper faces of the base and arm head as the sole means for bending the rod about one of them by and upon a swinging of the lever arm from the position it had when the rod was placed upon the base and lever head.

3. In a rod bender, a base providing a flat upper face and arranged to be held in a fixed position, a plurality of mutually spaced former pins fixed to the base and extending upwardly from its upper face, a lever arm having a head end portion pivoted to said base for a swinging of the arm about a fixed axis perpendicular to the upper base face and having a flat upper face coplanar with said base face, and a plurality of mutually spaced former pins fixed to the arm head in eccentric relation to said axis of swinging for the arm and extending upwardly from the upper face of said arm head, different combinations of at least three of said former pins of the base and arm head being so related as to cooperatively engage a rod supportedly placed upon said upper faces of the base and head for bending the rod about a pin of a selected combination in a plane parallel to the plane of said base and head faces as the lever arm is swung from its original position.

4. In a rod bender, a base providing a flat outer face, a set of former pins extending transversely from said base face in fixed relation to the base, a hinge pin extending transversely from said base, a lever arm mounted on said hinge pin for swinging about the pin axis and having a flat outer face coplanar with said base face, and a set of mutually spaced former pins extending fixedly from the lever in eccentric relation to the axis of swinging provided by the hinge pin, pins of the different sets being cooperative with a rod disposed against said outer faces of the base and arm as the sole means operative against the rod for bending it about one of the cooperative pins when the lever arm is swinging from the position it had when the rod was positioned for its bending.

5. A structure in accordance with claim 4 having the hinge pin extending no further from the base than said outer face of the mounted lever whereby a rod being bent may move across the hinging axis of the lever.

PETER L. PERAZZO.
